CLAIM

The ornamental design for a radiotelephone antenna, as shown and described.

DESCRIPTION

FIG. 1 is a front, bottom, and left side perspective view showing my new design for a radiotelephone antenna;

FIG. 2 is a bottom plan view thereof;

FIG. 3 is a right side elevational view thereof;

FIG. 4 is a front elevational view thereof;

FIG. 5 is a left side elevational view thereof;

FIG. 6 is a rear elevational view thereof; and

FIG. 7 is a top plan view thereof.

FIG. 8 is a front, bottom, and left side perspective view showing of our new design for a radiotelephone antenna in an alternate position;

FIG. 9 is a right side elevational view thereof;

FIG. 10 is a front elevational view thereof;

FIG. 11 is a left side elevational view thereof;

FIG. 12 is a rear elevational view thereof;

FIG. 13 is a bottom plan view thereof; and,

FIG. 14 is a top plan view thereof.

The broken line matter in the drawings is for illustrative purposes only and forms no part of the claimed design.
